FLUID MOTOR

Gunnar A. Wahlmark, Rockford, Ill.

Application December 20, 1939, Serial No. 310,137

11 Claims. (Cl. 121—119)

The invention relates generally to a fluid motor and more particularly to a fluid motor operable at a plurality of speeds, it being the general object of the invention to provide a new and improved multi-speed motor.

A more particular object of the invention is to provide a two-speed fluid motor of new and simplified construction and particularly adapted for use with a feed and rapid traverse drive for machine tools.

Other objects include the provision of a two-speed fluid motor of improved construction capable of producing a high torque at a slow speed for feed purposes, and a high speed for rapid traverse, and enabling the use of a constant displacement wobbler for driving the motor shaft.

Other objects and advantages will become apparent from the following detailed description taken in connection with the accompanying drawings, in which:

Fig. 1 is a diametrical sectional view of a fluid motor embodying the features of the invention and a line diagram of a hydraulic circuit for the motor.

Fig. 2 is a transverse sectional view taken approximately along the line 2—2 of Fig. 1.

Fig. 3 is a fragmentary and partially sectioned view of the motor in the position shown in Fig. 1, but adjusted for high speed operation.

Although the invention is susceptible of various modifications and alternative constructions, it is disclosed in the drawings and will hereinafter be described in a preferred embodiment. However, it is not intended that the invention is to be limited thereby to the specific construction disclosed, but it is intended to cover all modifications and alternative constructions falling within the spirit and scope of the invention as defined by the appended claims.

As disclosed herein, the invention is embodied in a two-speed fluid motor which comprises generally a casing 10 within which is housed fluid handling mechanism 11 of the reciprocating piston type, a rotatably mounted shaft 12, and conversion means 13 for converting the reciprocating motion of the fluid handling pistons into rotary motion of the shaft. An inlet passage 14 and an outlet passage 15 are formed in one end of the casing 10 and cooperate with suitable ports and a valve 16 to supply fluid under pressure to the fluid handling mechanism, and for discharging the spent fluid after it has functioned to impart a working stroke to the pistons of the fluid handling mechanism.

The casing 10, as illustrated herein, comprises a plurality of sections 20, 21, 22, 23 and 24 which are secured together to form a unit by means of a plurality of bolts 25 extending through the sections 24, 23, 22 and 21, and into threaded engagement with the section 20. Section 21 con-

stitutes a cylinder block and has a thicker portion 21' formed with a plurality of bores 26, herein nine in number (see Fig. 2), disposed longitudinally of the casing and arranged annularly about the shaft 12. The casing section 22 is in the form of a port plate and abuts against the head or left hand end (see Fig. 1) of the cylinder block and cooperates therewith to complete the cylinder block. The port plate 22 is formed with a plurality of recesses 27 larger in diameter than the bores 26 and registering therewith to complete the head ends of the cylinders formed by the bores. Opening to each of the recesses 27 is a cylinder port 28 which, as best seen in Fig. 2, is somewhat elliptical in shape, being formed by three apertures approximating the shape of an ellipse. The cylinder block 21 and the port plate 22 are secured together by means of a sleeve 29 inserted through a central bore formed in the cylinder block 21. The sleeve 29 is at one end threaded into the port plate 22 and at the other end is formed with an annular flange 29'. This flange does not bear directly against the end of the portion 21' of the section 21, but bears against bushings 30 which are inserted one in the rod end of each bore 26, and in turn are formed with a radial flange 30'.

As illustrated herein, the fluid handling mechanism 11 comprises a first series of sleeve-like pistons 31 reciprocably mounted in the cylinder bores 26, and a second series of cylindrical pistons 32 of substantially smaller diameter. These smaller pistons 32 are reciprocable in the sleeve-like pistons 31 and are formed as integral but reduced portions of piston rods 33 which extend slidably through the bushings 30 to be guided thereby. The juncture of the rod 33 and the piston 32, of course, provides an annular shoulder 34 against which the larger piston 31 bears in order that the piston 31 may impart a power stroke to the rod 33. An annular groove 35 is formed in the reduced portion 32 adjacent the shoulder 34 for a purpose which will become more apparent hereinafter.

The conversion means 13 is herein of the wobble plate type and has a unique construction enhancing the effectiveness of that type of conversion means. This conversion means is broadly claimed in my copending application, Serial No. 349,163, filed August 1, 1940. Forming the basic part of the conversion means is a wobble plate 38 secured to the shaft 12 by means of a key 39. At one end the plate 38 bears against an annular shoulder 40 formed by an enlarged portion of the shaft 12, while at its other end it bears against the inner race 41 of a thrust ball bearing 42, the outer race 43 of which is mounted in the right hand end of the portion 20 of the motor casing, as viewed in Fig. 1. The outer race 43 in turn bears against an outer race 44 of a ball bearing 45, the inner race 46 of which

bears against the inner race 41 of the thrust bearing 42. The outer race 44 of the bearing 45 is limited in its outward movement by an annular shoulder 47 formed in the portion 20 of the motor casing, while the plate 38 and the inner races 41 and 46 are firmly retained on the shaft 12 by a nut 48 threaded onto the shaft. A rotary seal RS prevents leakage of fluid outwardly along the shaft 12, and a roller bearing 48' supports the inner end of the shaft.

The wobble plate 38 is, of course, of non-uniform construction and comprises a hub 38' and a radial flange 38" disposed in a plane oblique to the axis of the shaft 12 and having closely adjacent its periphery a race 49 for a set of rollers 50. An annular member 51 provides the other race 52 for the rollers 50, which rollers incidentally have a diameter several times their width in order that there may be a substantially one hundred per cent rolling contact of the rollers 50. The face of the member 51 opposite the race 52 is engaged by the projecting end of the rods 33 and, in order that this engagement between the rods 33 and the member 51 may be most effective, the ends of the rods 33 are made conical so that they will have a straight line contact with the face of the ring 51.

To retain the member 51 in its proper relationship with respect to the plate 38 and to preload the rollers 50, a ball bearing 54 is provided which has its outer race formed in an annular flange 55 which is integral with the member 51. The inner race of the bearing 54 is formed in a collar 56 carried by the hub 38' of the wobble plate and is held against rotation by a pin 57 which projects into a key-way 58 formed longitudinally of the hub 38'. The collar 56 is retained in its position on the wobble plate by means of a split ring 59 retained by fitting into an annular groove formed in the hub of the wobble plate for that purpose. It is to be noted that, with this construction, the rollers 50 act on the outermost portion of the wobble plate 38, while the engagement of the rods 33 with the member 51 is somewhat inwardly of the rollers 50. It will be recognized that the conversion means which connects the pistons with the shaft and which includes the wobble plate 38 and the annular member 51, is applicable to hydraulic devices of this general design, whether they be operated as motors or as pumping mechanisms.

In the present instance, the pistons 31 and the pistons 32 operate jointly and simultaneously to effect a drive of the shaft 12 at a low speed when the fluid motor is supplied with a predetermined volume of fluid under pressure. Pistons 32, being of substantially smaller cross sectional area than both pistons combined, may be referred to as high speed pistons, and when operated by an equal volume of fluid under pressure are effective to rotate the shaft at a higher speed. The means for supplying fluid to actuate the pistons jointly or the high speed pistons separately to attain these results will now be described.

The passage 14, the passage 15 and the valve 16, together with the ports for conducting fluid to and from the cylinder ports 28, are similar to those illustrated and described in my Patent No. 2,190,812, issued February 20, 1940. Thus the left end of the casing 10, as viewed in Fig. 1, is completed by the sections 23 and 24, with the section 24 in the form of a cap or head containing the supply and exhaust passages 14 and 15. The section 23 is in the form of an annular ring 75

spacing the section 24 from the port plate 22 so as to form a valve chamber 16'. Inlet passage 14 communicates with the outer edge of the valve chamber 16' by means of a plurality of arcuate ports 60 (see Fig. 2). Exhaust passage 15 communicates with a plurality of arcuate ports 62 communicating with the valve chamber 16' at points spaced inwardly from the periphery thereof, as most clearly shown in Fig. 1. The inlet ports 60 and the exhaust ports 62 are formed concentrically with the shaft 12, as are also the cylinder ports 28.

The cylinder ports are herein controlled by means of the valve 16 which is adapted to effect the opening and closing of the ports and are alternately connected to the inner and outer portions of the valve chamber 16' in timed relation with the reciprocation of the pistons in a manner obtaining a maximum period of port opening, and rapid opening and closing of the ports. The valve 16 is circular in form and is mounted by means of a ball bearing 63 on a stud 61 formed eccentrically (see Fig. 2) on the inner end of the shaft 12 and projecting into the space between the port plate 22 and the section 24.

The faces of the valve 16 are ground so as to have a fluid-tight sliding fit with the adjacent faces of the port plate 22 and the section 24. The valve is most readily pictured as a wheel having a hub 64 and a rim 65 secured to the hub by a plurality of spokes 66 of reduced thickness so as to form annular recesses 67 and 67' in opposite faces of the valve, which recesses are connected by means of circular openings 68 formed between the spokes. The recess 67 is so disposed that it is always in communication with the arcuate exhaust ports 62, and is of such width that in any position of the valve several of the cylinder ports 28 open in whole or in part thereto. The rim 65 has a radial thickness slightly greater than the width of the port 28, so that in any position of the valve 16 a plurality of ports 28 are disposed in whole or in part outwardly of the valve 16 so as to communicate with the peripheral portion of the valve chamber 16' which is supplied by the inlet ports 60. Thus the rim 65 of the valve, during rotation of the shaft 12 and the simultaneous orbital movement of the valve, connects the cylinder ports 28 with the inlet ports 60 during the intake strokes of the pistons, and connects the cylinder ports 28 with the outlet ports 62 during the exhaust strokes of the pistons. Furthermore, when a piston is at one end or the other of its stroke, the rim 65 closes the corresponding cylinder port 28. In the operation of the valve, the movement of the rim 65 with respect to the cylinder ports 28 is such that the ports are opened and closed very rapidly because the eccentric stud 61 is then moving directly toward or away from the particular cylinder port.

As previously stated, the shaft 12 will be driven at its low speed by the joint operation of the pistons 31 and 32, while the shaft will be driven at its high speed by the sole operation of the pistons 32. Power strokes are imparted to the pistons by the fluid under pressure admitted through the cylinder ports 28, and they are moved through their return strokes by the wobble plate 38.

In order that the pistons 32 may operate independently of the pistons 31, provision is made to admit the working fluid to the rod end of the cylinders 26. To that end, the portion 21, that is, the cylinder block, is formed with an an-

nular groove 10 communicating with each of the cylinders 26 just inwardly of the sleeve 30. This groove in turn is connected by a passage 71 with a control port 72. Thus, when fluid is supplied to the rod end of the cylinders 26 under pressure, the pistons 31 are forced and held against the head end of the section 22 where they are held while the smaller pistons 32 operate to drive the shaft at a high speed. The position of the parts during such high speed operation is best seen in Fig. 3, special clearance having been provided to permit of such separation of the pistons 31 from the rods 33 when the rods are at the end of their exhaust stroke. The retention of the pistons 31 in the head ends of the cylinders during such operation is assured because the pressure fluid supplied through the annular groove 10 is always substantially uniform, while the pressure supplied to the head end of the pistons 31 is intermittent due to the opening and closing of the ports 28 by the valve 16.

The fluid supplied to the rod end of the cylinders 26 may be governed in a variety of ways by any suitable means, such as a valve, for effecting the opening and closing of a conduit connected with the control port 72 and conducting pressure fluid. In Fig. 1 there has been illustrated a line diagram of a hydraulic circuit including this motor and a pump 74 connected by an intake conduit 75 to a reservoir 16 and by a conduit 77 to the intake passage 14 of the motor. A conduit 78 branches off from the conduit 77 and leads to a control valve 79 having one conduit 80 leading therefrom to the port 72 and a return conduit 81 leading to the reservoir 16. The valve 79 may be of any construction, such that at predetermined times or upon predetermined operation pressure fluid from the pump 74 will be supplied to the rod end of the cylinders 26 through the port 72 and connecting passage 71, while at other times the conduit 78 is closed and the conduit 80 connected to the return conduit 81. The circuit is completed by a main return conduit 82 leading from the exhaust passage 15 to the tank 76.

The operation of the motor disclosed herein, when connected in circuit as shown, would be as follows: If it is assumed that the valve 79 is adjusted to the position shown in Fig. 1, namely, wherein the conduit 78 is blocked and the rod ends of the cylinders are connected to the tank 76, the fluid supplied by the pump 74 would be effective to act upon both the small piston 32, as well as the large annular piston 31. Because of the increased displacement of the motor under such circumstances, it would operate at low speed with the power of the motor, of course, correspondingly increased due to the larger area of the combined pistons. To obtain a higher speed of operation for the same displacement of the pump 74, it is only necessary to rotate the valve 79 ninety degrees in a counter-clockwise direction, as viewed in Fig. 1, which would then connect the conduits 78 and the conduit 80 to supply fluid to the rod ends of the cylinders through the piston 71 and groove 14 communicating therewith. The pressure fluid so supplied to the rod end of the cylinders would act upon the piston 31 of each cylinder and during the time that the head end of the cylinder is connected to the discharge port 15 would shift the piston 31 against the plate 22 to the position shown in Fig. 3. This would expose the entire rod end area of the piston 31, while rendering a major portion of the head end area of the pis-

ton 31 ineffective so that the piston could readily be retained against reciprocation in the position shown in Fig. 3 by the fluid in the rod end of the cylinder. With the piston 31 held stationary, the fluid supplied through the intake port 14 would, of course, act only upon the small pistons 32 and thus because of the reduced displacement of the motor would cause the same to operate at a higher speed.

I claim as my invention:

1. A two-speed fluid motor comprising, in combination, a casing, a cylinder therein, an annular piston reciprocable in the head end of said cylinder, a bushing fixed in the rod end of said cylinder, an elongated member having a portion slideable in said bushing and in all positions projecting from the rod end of said cylinder to form a piston rod, a reduced portion at the other end of said member slideable in said annular piston to form a high speed piston, and an annular shoulder at the base of the reduced portion providing an abutment through which the annular piston may impart a power stroke to said member, said member being capable of independent movement through a power stroke, a rotatably mounted shaft, means for converting the reciprocatory motion of said cylindrical member into rotary motion of the shaft, valve means driven by said shaft for controlling the supply of operating fluid to the head end of said cylinder, the fluid acting on both pistons to effect simultaneous operation thereof and operation of the motor at a low speed, and a passage for conducting operating fluid to the rod end of the cylinder intermediate said annular piston and said bushing to balance the fluid acting on the opposite end of said annular piston to render the same inoperative and effect high speed operation of the motor through said high speed piston only.

2. A fluid motor comprising, in combination, a casing, a cylinder therein, an annular piston reciprocable in the head end of said cylinder, a bushing fixed in the rod end of said cylinder, an elongated member having a portion slideable in said bushing and in all positions projecting from the rod end of said cylinder to form a piston rod, a reduced portion at the other end of said member slideable in said annular piston to form a high speed piston, and an annular shoulder at the base of the reduced portion providing an abutment through which the annular piston may impart a power stroke to said member, said member being capable of independent movement through a power stroke, a rotatably mounted shaft, means for converting the reciprocatory motion of said elongated member into rotary motion of the shaft, valve means driven by said shaft for controlling the supply of operating fluid to the head end of said cylinder, and means to balance the fluid acting on the head end of said annular piston to render the same inoperative and effect high speed operation of the motor through said high speed piston only.

3. A fluid motor comprising, in combination, a casing, a cylinder therein, a bushing in the rod end of said cylinder, a cylindrical member having a portion forming a piston rod slidably mounted in said bushing and in all positions projecting through the bushing outwardly of the cylinder, said cylindrical member having a reduced end portion forming a piston and an annular shoulder, an annular member slidably mounted in the head end of said cylinder to form a piston and having a bore in which the first mentioned piston reciprocates, a rotatably mounted shaft, means

for converting the reciprocatory motion of said cylindrical member into rotary motion of the shaft, and means for supplying pressure fluid to said cylinder intermediate said bushing and said annular piston to render said first mentioned piston only operative for high speed operation of the motor.

4. A two-speed fluid motor comprising, in combination, a casing, a plurality of annularly arranged cylinders in said casing, a rotatably mounted shaft concentric of said cylinders, valve means driven by said shaft to control the flow of operating fluid to and from the head end of said cylinders, a first piston slidably mounted in each cylinder, a second piston slidably mounted in said first piston and exposed to the pressure fluid in the head end of the cylinder to be jointly reciprocable with said first piston to effect operation of the motor at low speed, means connecting said pistons to said driven shaft, and means for conducting operating fluid to the rod end of said cylinders to render said first pistons ineffective and cause operation of the motor at high speed through said second pistons only.

5. A two-speed fluid motor comprising, in combination, a casing, a plurality of annularly arranged cylinders in said casing, a rotatably mounted shaft concentric of said cylinders, valve means driven by said shaft to control the flow of operating fluid to and from the head end of said cylinders, a first and a second piston reciprocable in each cylinder and each exposed to the operating fluid in the head end of the cylinder, a bushing in the rod end of each cylinder, a piston rod projecting through said bushing and having a fluid-tight sliding fit therewith, said piston rod having a connection with at least one of said pistons permitting the piston to impart a working stroke to said rod while permitting said rod to move through a working stroke independently of the other piston, means for converting the reciprocatory motion of said rods into rotary motion of said shaft, and means for conducting operating fluid to the rod end of said cylinders to render one of said pistons ineffective and cause operation of the motor at a higher speed.

6. A two-speed fluid motor comprising, in combination, a casing, a plurality of annularly arranged cylinders in said casing, a rotatably mounted shaft concentric of said cylinders, valve means driven by said shaft to control the flow of operating fluid to and from the head end of said cylinders, a first piston slidably mounted in each cylinder and a second piston slidably mounted in said first piston, both pistons being exposed to the pressure fluid in the head end of said cylinder to be jointly acted upon by the pressure fluid in the head end of the cylinder to effect operation of the motor at a first speed, a bushing in the rod end of each cylinder, a piston rod projecting through the bushing and having a fluid-tight sliding fit therewith, one of said pistons being integral with said piston rod, the other of said pistons being adapted to impart a working stroke to said piston rod and said rod being movable through a working stroke independently of said last mentioned piston, means for converting the reciprocatory motion of said piston rods into rotary motion of said shaft, and means for conducting operating fluid to the rod ends of the cylinders to counterbalance the effect of the operating fluid on the pistons with respect to which the piston rods have independent movement.

7. In a fluid motor, a casing, a cylinder in said

casing, a first piston reciprocable in said cylinder having a bore extending longitudinally thereof and opening through both ends thereof, a second piston reciprocable in the bore of said first piston, a piston rod adapted to have a working stroke imparted thereto by both of said pistons and to be movable through a working stroke independently of at least one of said pistons, a port through which operating fluid may be supplied to the head end of said cylinder, and a port through which operating fluid may be simultaneously supplied to the rod end of said cylinder to hold one of the pistons against reciprocation.

8. In a fluid motor, a casing, a cylinder in said casing, a first piston reciprocable in said cylinder having a bore extending longitudinally thereof and opening through both ends thereof, a second piston reciprocable in the bore of said first piston, a piston rod adapted to have a working stroke imparted thereto by both of said pistons and to be movable through a working stroke independently of at least one of said pistons, a port through which operating fluid may be supplied to the head end of said cylinder, and means

15 20 25 30 35 40 45 50 55 60 65 70 75 80 85 90 95

selectively operable for applying fluid under pressure simultaneously against both ends of the piston with respect to which said piston rod has an independent working stroke thereby holding said piston against reciprocation.

9. A two-speed fluid motor comprising, in combination, a casing, a plurality of annularly arranged cylinders in said casing, a rotatably mounted shaft concentric of said cylinders, valve means driven by said shaft to control the flow of operating fluid to and from the head end of said cylinders, a first and a second piston reciprocable in each cylinder and each exposed to the operating fluid in the head end of the cylinder, means for converting the reciprocatory motion of said pistons into rotary motion of said shaft, and means for conducting operating fluid to the rod end of said cylinders to render one of said pistons ineffective and cause operation of the motor at a higher speed.

10. A two-speed fluid motor comprising, in combination, a casing, a plurality of annularly arranged cylinders in said casing, a rotatably mounted shaft concentric of said cylinders, valve means driven by said shaft to control the flow of operating fluid to and from the head end of said cylinders, a first and a second piston reciprocable in each cylinder and each exposed to the operating fluid in the head end of the cylinder, means for converting the reciprocatory motion of said pistons into rotary motion of said shaft, and fluid means for rendering one of said pistons ineffective to cause operation of the motor at a higher speed.

11. A two-speed fluid motor comprising, in combination, a casing, a plurality of cylinders in said casing, a rotatably mounted shaft, valve means driven by said shaft to control the flow of operating fluid to and from the head end of said cylinders, a first and a second set of pistons reciprocable in the cylinders each piston exposed to the operating fluid in the head end of the cylinders, means for converting the reciprocatory motion of said pistons into rotary motion of said shaft, and means for simultaneously applying operating fluid to both ends of the pistons of one set to render that set of pistons ineffective and cause operation of the motor at a higher speed.
